UNITED STATES PATENT OFFICE

2,290,508

VARIABLE CAPACITOR

George L. Usselman, Port Jefferson, and Ralph E. Franklin, Patchogue, N. Y., assignors to Radio Corporation of America, a corporation of Delaware

Application June 27, 1939, Serial No. 281,344

8 Claims. (Cl. 175—41.5)

This invention relates to a new and novel variable condenser, and is similar in scope to a vernier variable condenser described in the Franklin and Thorne patent application, filed June 28, 1939, S. N. 281,642, except that instead of the movable electrode being of metal, both electrodes are fixed and the condenser capacity is changed by movement of a solid dielectric member which is interposed between two fixed electrodes, the variable feature being the change in the amount of dielectric between fixed electrodes.

An object of this invention is to simplify and improve adjustable variable capacitors for frequency measuring sets and similar apparatus.

Another object of this invention is to improve the type of variable condenser known in the prior art having a micrometer head for moving the variable element with a suitable index therefor.

Still another object of this invention is to provide a variable vernier condenser whose capacity remains substantially constant regardless of temperature changes, which is accomplished by the use of special materials having a low coefficient of thermal expansion.

A feature of this invention is the arrangement of the ordinary micrometer head with two fixed electrodes and a variable dielectric element.

This invention will best be understood by referring to the accompanying drawing, in which:

Fig. 1 is a longitudinal section of one embodiment of this invention;

Fig. 2 is a longitudinal section of another embodiment of this invention; and

Fig. 3 is a partial section of a modification of the embodiment shown in Fig. 1.

Referring now in detail to Fig. 1 of the drawing, the condenser of this invention comprises an outer cylindrical electrode 1 made preferably of "Invar" or other similar metal of low coefficient of thermal expansion. 2 is another fixed electrode in the form of a rod which is supported from electrode 1 by means of an insulator 4 by screws 2a. Member 4 is secured to electrode 1 by screws 4a. A cylinder 3 of insulating material, such as fused quartz, is secured to and rotates with one end of a micrometer 5 by means of a screw 5a which passes through a metal sleeve 8 and forms the variable element. Micrometer head 5 is of the well-known machinist's type of micrometer having a barrel which rotates on a thimble with a spindle to which member 3 is secured, the barrel having an internal thread of forty turns per inch and turning on a threaded

nut or thimble which has located on its outside surface circumferential divisions from "1" to "10" spaced apart from each other every tenth of an inch. These divisions are further subdivided in four equal parts. The barrel portion of micrometer 5 has its outer periphery divided in twenty-five divisions in order that one turn will represent twenty-five thousandths of an inch on a horizontal index, located just above the subdivisions on the thimble. The condenser capacity is varied by movement of the outer barrel which in turn moves the solid dielectric variable element 3 in and out of mesh between electrodes 1 and 2. A yoke 6 is provided for mounting the micrometer head and positioning member 3 concentric with electrodes 1 and 2 on a panel 7 of insulating material by means of screws 6a which mounts the entire capacitor in any suitable position. Electrode 1 is secured to panel 7 by means of screws 1a or, if desired, screws 6a may be extended to pass through both members 6 and 1 to serve as a common mounting means. Electrical connection is made to electrode 1 by means of a terminal 9 and also a terminal 10 is provided for making connection to inner electrode 2.

In this form of condenser, any small eccentricity in the mounting of electrode 2 within casting electrode 1 will not cause a variation in the rate of capacity change when changing the position of the solid dielectric 3 by means of rotating the micrometer head 5. If the variable or solid dielectric member 3 is made of fused quartz or other material of a high dielectric constant, the condenser can be made much smaller for the same capacity than similar types of capacitors using air as the dielectric.

Referring now to Fig. 2, the construction is somewhat modified but is generally similar to the structural arrangement of Fig. 1, except for reasons of economy in cost and space requirement. As shown by the drawing, an electrode 22 is carried by the cylindrical insulator 23. The arrangement of being secured to micrometer head 5 is similar to that of Fig. 1. The outer electrode 21, however, does not require the use of a supporting insulator but is left open to receive a flexible lead 24 which is fastened to electrode 22 by means of a screw 25. Electrical connections are made to the electrodes by means of terminals 26 and 27.

As shown by Fig. 3 of the drawing, electrode 1 and insulator 4 may be combined as one piece and constructed of insulation of fused quartz or molded ceramic material. Electrode 31 is formed on the inner cylindrical surface of the insulator

34 which is disposed by chemical means, as by evaporation in a vacuum. Electrode 32 is also in the form of a coated metallic film located on the cylindrical extension portion of member 34, suitable connections being made to the coated film by means of a wire 35 passing through the upper wall of insulator 34 and soldered to coating 31. Likewise, electric connection is made to coating 32 in a similar manner by means of a wire 36 passing through the central portion of insulator 34.

In all the above embodiments of the condenser, the interposed dielectric material should more nearly fill the space between the electrodes when the condenser is set for the maximum capacity position than is shown in the drawing, the larger spaces being indicated merely for the purpose of clarity.

Although only a few embodiments of this invention are described, it is to be distinctly understood that it should not be limited to the precise arrangement shown.

What is claimed is:

1. A variable condenser of the solid dielectric type comprising a metallic casing acting as one electrode, an insulator secured to and forming one end of said casing, a second electrode secured to said insulator, a solid dielectric member interposed between said electrodes, and means to move the position of said solid dielectric member to change the capacity of said condenser.

2. A variable condenser of the solid dielectric type comprising a metallic casing acting as one electrode, an insulator secured to and forming one end of said casing, a second electrode secured to said insulator, a solid dielectric member of fused quartz interposed between said electrodes, and means to move the position of said solid dielectric member to change the capacity of said condenser.

3. A variable condenser comprising a metallic casing acting as one electrode of said condenser, an insulator secured to and forming one end of said casing, a second electrode secured to said insulator, a solid dielectric having a dielectric constant greater than the dielectric constant of air interposed between said electrodes, and means to vary the capacity of said condenser by changing the position of said solid dielectric member which is interposed between said electrodes.

4. A variable condenser of the solid dielectric type comprising a metallic casing acting as one electrode, an insulator secured to and forming one end of said casing, a second electrode secured to said insulator, a solid dielectric member interposed between said electrodes, and means to move the position of said solid dielectric to change the capacity of said condenser, said means comprising a threaded member secured to and rotating with said solid dielectric.

5. A variable condenser of the solid dielectric type comprising a metallic casing acting as one electrode, said casing secured to a panel mounting member, an insulator secured to and forming one end of said casing, a second electrode secured to said insulator, a solid dielectric member interposed between said electrodes, and means to move the position of said solid dielectric to change the capacity of said condenser, said means comprising a yoke having supported thereto a threaded member which is arranged to rotate with said solid dielectric.

6. A variable condenser comprising a cylindrical metallic casing acting as one electrode of said condenser, a disc-like insulator secured to and forming one end of said casing, a rod-like electrode secured to the center of said insulator, a solid dielectric member interposed between said electrodes, and means to move said solid dielectric to change the capacity of said condenser.

7. A variable condenser comprising a cylindrical metallic casing acting as one electrode of said condenser, a disc-like insulator secured to and forming one end of said casing, a rod-like electrode secured to the center of said insulator, a solid dielectric hollow cylindrical member interposed between said electrodes, and means to move said dielectric to change the capacity of said condenser.

8. A variable condenser comprising two fixed electrodes in electrostatic relationship with each other, at least one of said fixed electrodes being in the form of a rod-like metallic member, a disc-like insulating member supported from the other electrode for securing said rod-like metallic member thereto, a solid dielectric member interposed between said electrodes, and means to move said solid dielectric to change the capacity of said condenser.
